UNITED STATES PATENT OFFICE.

JONAS D. GOTTSCHALK, OF NEW YORK, N. Y.

FASTENER FOR NECK-WEAR.

SPECIFICATION forming part of Letters Patent No. 373,930, dated November 29, 1887.

Application filed June 3, 1887. Serial No. 240,125. (No model.)

To all whom it may concern:

Be it known that I, JONAS D. GOTTSCHALK, of the city, county, and State of New York, have invented certain new and useful Improvements in Fasteners for Neckties, Bows, &c., of which the following is a specification.

This invention relates to an improved fastener for neckties, bows, and other neck-wear, by which the same can be held on a collar-button without riding the collar, the fastener being especially designed to be used with stand-up collars and readily applied to the article of neck-wear without stitching or otherwise permanently fastening the same; and the invention consists of the combination, with a necktie, bow, or other article of neck-wear, of a fastening device formed of a tapering body having a central recess for the shank of the collar-button, and forwardly-bent retaining-flanges that are applied to the face-band or loop of the necktie, bow, &c., as will appear more fully hereinafter, and finally pointed out in the claim.

In the accompanying drawings, Figure 1 represents a rear elevation of a bow with my improved fastening device. Fig. 2 is a horizontal section of the same; and Fig. 3 is a top view of the blank, from which the fastener is made.

Similar letters of reference indicate corresponding parts.

In the drawings, A represents a bow, necktie, or other article of neck-wear; B, a fastener on the same, which is preferably made of sheet metal, with a slightly-tapering body having a central recess, a, extending downward from

the upper edge of the fastener, for engagement with the shank of the collar-button.

The fastener B is provided with forwardly-bent flanges b b, that extend parallel to the body of the fastener, so as to nearly abut against each other, said flanges retaining the fastener B on the loop or face-band of the bow or other article of neck-wear, and permitting it to slide or move thereon without requiring any other fastening device, such as stitching, riveting, and the like.

The fastener is applied by its recess a to the collar-button in the same manner as other fasteners of this class, and retains the bow or necktie in position on the collar without permitting the riding of the same. It is conveniently applied and forms a simple and cheap device for retaining the bow or other article of neck-wear on the collar-button of a stand-up collar.

Having thus described my invention, I claim as new and desire to secure by Letters Patent—

A necktie-fastener, substantially as described, consisting of a tapered body of flat metal provided with a downwardly-extending notch or recess, and end flanges bent rearwardly and then parallel with the front plate, for the purpose of being removably connected with the neck-wear, as set forth.

In testimony that I claim the foregoing as my invention I have signed my name in presence of two subscribing witnesses.

JONAS D. GOTTSCHALK.
